UNITED STATES PATENT OFFICE.

BENJAMIN JEWETT RICKER, OF GRINNELL, IOWA.

APPAREL-GLOVE.

No. 873,608.

Specification of Letters Patent.

Patented Dec. 10, 1907.

Application filed September 10, 1906. Serial No. 333,943.

To all whom it may concern:

Be it known that I, BENJAMIN JEWETT RICKER, a citizen of the United States, residing at Grinnell, in the county of Poweshiek 5 and State of Iowa, have invented a certain new and useful Apparel-Glove, of which the following is a specification.

My object is to provide an apparel glove especially designed for use by persons who 10 desires to use the glove when wearing cuffs and to inclose and protect the cuffs from dust and dirt and also to provide a glove of this kind that will closely and tightly fit the wearer's hand and wrist and have a maximum 15 amount of elasticity and flexibility and yet be made of relatively thick leather that will not readily wear out, and further to provide a glove of this kind that will allow a considerable degree of ventilation for the 20 wearer's hand without permitting the entrance of dust or dirt.

My invention consists in forming a glove with rows of perforations therein so arranged that they will not only serve the purpose of 25 ventilating the wearer's hand, but will also serve to provide elasticity and flexibility at the points where the glove is bent or stretched when in use and also in the arrangement of the rows of perforations so that they will 30 permit a certain degree of lateral expansion of the glove so that it may closely and accurately fit hands of different sizes and further in the shape of the gauntlet portion and in providing a relatively stiff and heavy gauntlet 35 portion with a flexible V-shaped gore and also with an adjusting strap so arranged that the heavy gauntlet portions may be tightened by the adjusting strap around the wearer's 40 wrist without affecting the stiff heavy gauntlet portion and only affecting the soft flexible gore portion, as hereinafter more fully set forth, pointed out in my claims and illustrated in the accompanying drawings, in which

45 Figure 1 shows a rear elevation of the complete glove provided with my improvements, and Fig. 2 shows a front view of same.

Referring to the accompanying drawings, I have used the reference numeral 10 to 50 indicate the palm portion of the glove, 11 the underside of the finger portions, 12 the back of the hand portion and 13 the back of the finger portions. The thumb is indicated by the numeral 14. The hand portion of the 55 glove, just referred to, is made of relatively heavy leather and at the back of each finger

portion, I have formed three rows of perforations 15 and along both side edges of the back portion 12, I have extended the rows of perforations to a point near the wrist and at 60 the central portion of the back, I have extended the rows of perforations on the two middle fingers over the knuckle portions of the back. By this arrangement of the rows of perforations, the finger portions may be 65 made to fit the wearer's fingers because of the flexibility permitted by the rows of perforations at the back of the fingers and the glove will also tightly fit the palm of the 70 wearer's hand because of the flexibility permitted by the rows at the sides of the back portion of the hand.

Furthermore the wearer may readily and easily close his hand because of the rows of perforations over the knuckle portions and the joints of the fingers. This arrangement of the rows of perforations, while permitting flexibility and elasticity of the glove in certain directions provides for adapting the glove to fit hands of different sizes and yet 80 the rows of perforations are so arranged that they do not permit the parts of the hand portion of the glove to stretch in directions that would interfere with accurate fitting and furthermore all of the perforations are so arranged that they will permit free ventilation of the hand and yet will not be in such positions that dust or dirt will enter through them when the glove is used for ordinary 85 purposes.

The gauntlet which is preferably made of thick heavy leather is indicated by the reference numeral 16 and is so shaped that it will freely admit the wearer's sleeve and cuff. At the center of the back portion of the gauntlet 90 is a V-shape opening with its small end at the rear and spaced apart a considerable distance from the rear end of the gauntlet. This opening is covered or filled by a soft flexible gore so that the back of the gauntlet portion adjacent to the wrist may freely expand or contract to a certain extent so much so that after the wearer's hand has passed through the wrist portion of the glove, the 100 said wrist portion may be closely fitted to the wearer's wrist. To provide for this adjustment, I have fixed a small strap 18 to one side of the wrist portion and a wider strap 19 to the other side and on the strap 19 is a slotted plate 20 through which the end 105 of the strap 18 is passed, as shown in Fig. 1, and by pulling upon this strap, the wrist

portion of this glove is constricted and the strap 18 will be held in any position of its adjustment in which it may be placed. It may, however, be released and the glove expanded at the wrist by simply pulling out upon the end of the strap 19. The particular form of this fastening device comprises no part of my present invention.

In practical use, the glove is placed upon the wearer's hand in the ordinary way and after it is adjusted to position, the strap 18 is pulled to cause the wrist portion of the glove to tightly fit about the wearer's wrist. The shape of the gauntlet permits the wearer's cuff and sleeve to enter it and assume its ordinary position with relation to the wearer's hand. The rows of perforations, arranged as shown and for the purposes herein set forth, permits the glove to securely fit the wearer's hand and fingers and to freely stretch at the required places when the wearer's hand is opened or closed to thus provide a tight fitting glove made of relatively heavy leather and further ventilation may take place through the rows of perforations.

Having thus described my invention, what I claim and desire to secure by Letters Patent of the United States, therefor is—

1. An apparel glove, comprising a hand portion, a gauntlet portion formed of rela-

tively stiff and unyielding material, and designed to receive a wearer's sleeve and cuff, and formed with an opening extending from the forward end portion of the gauntlet portion to a point spaced apart from the rear end of the gauntlet portion, a flexible gore covering said opening, and means for adjusting the parts of the gauntlet portion adjacent to said opening, whereby the end of the gauntlet portion that is adjacent to the glove portion may be adjusted without affecting the rear end of the gauntlet portion.

2. An apparel glove comprising a hand portion, a gauntlet portion connected therewith, and made of relatively stiff and unyielding material, and formed with a tapered opening at the back thereof, said tapered opening having its wide end adjacent to the hand portion, and having its small end spaced apart a considerable distance from the free end of the gauntlet, a flexible gore secured in said opening, and straps attached on opposite sides of the opening for drawing together the end of the gauntlet adjacent to the hand portion, without affecting the body of the gauntlet.

Des Moines, Iowa, August 24, 1906.
